(57) **CLAIM**

The ornamental design for a vegetable chopper, as shown and described.

DESCRIPTION

FIG. 1 is a perspective view of a vegetable chopper, showing my new design;

FIG. 2 is another perspective view thereof;

FIG. 3 is a perspective view of the design in a detached status;

FIG. 4 is a perspective view of the design in a detached and use status;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a perspective view of one part of the design;

FIG. 12 is another perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is a perspective view of another part of the design;

FIG. 20 is another perspective view thereof;

FIG. 21 is a front view thereof;

FIG. 22 is a rear view thereof;

FIG. 23 is a left side view thereof;

FIG. 24 is a right side view thereof;

FIG. 25 is a top plan view thereof;

FIG. 26 is a bottom plan view thereof; and,

FIG. 27 is a perspective view of all parts in a detached status.

The broken line showing of the vegetable chopper is for the purpose of illustrating article and forms no part of the claimed design.

The parts of the vegetable chopper are shown separately for clarity of illustration.
